CLAIM

The ornamental design for a mask cushion, as shown and described.

DESCRIPTION

FIG. 1 is a perspective view of a first embodiment of a mask cushion showing our design;

FIG. 2 is a front view thereof;

FIG. 3 is a top view thereof;

FIG. 4 is a rear view thereof;

FIG. 5 is a rear view of a second embodiment of a mask cushion thereof;

FIG. 6 is a front view thereof; and,

FIG. 7 is a side view thereof.

Where included, broken lines showing environment or structure are for illustrative purposes only and form no part of the claimed design.

The use of stippling is used to indicate shading.
